HOOD CATCH

Filed May 3, 1928

INVENTOR.
RAYMOND G. MOORE.
BY
John Mather.
ATTORNEY.

UNITED STATES PATENT OFFICE

RAYMOND G. MOORE, OF BRIDGEPORT, CONNECTICUT, ASSIGNOR TO THE BASSICK COMPANY, OF BRIDGEPORT, CONNECTICUT, A CORPORATION OF CONNECTICUT

HOOD CATCH

Application filed May 3, 1928. Serial No. 274,817.

The present invention relates to automobile hood catches, and has for an object to provide an improved latch of the type adapted in addition to holding down the hood, to 5 also force the same inwardly, and thereby effectively secure it against looseness and rattling. A further object is to provide such a catch which will compensate for variations in the position of the hood, so that wear and 10 inaccurate placing of the catch will not affect its proper functioning. Another object is to provide a catch in which there will be metal to metal contact between the compensating parts, but so arranged and cooperat- 15 ing as to always maintain a non-rattling relation, free of squeaks and scraping noises, and to this end it is particularly proposed in the present embodiment to provide a compensating lever like keeper upon the hood 20 adapted through the downward pulling action of the catch to draw the latter inwardly, and further to provide a cooperative camming means between the hood and catch adapted to produce both a downward and in- 25 ward pressure.

With the above and other objects in view, an embodiment of the invention is shown in the accompanying drawings, and this embodiment will be hereinafter more fully de- 30 scribed with reference thereto, and the invention will be finally pointed out in the claims.

In the drawings:

Fig. 1 is a side elevation, partly in section, of a hood catch, according to the present 35 embodiment of the invention;

Fig. 2 is a front elevation of the keeper and hood;

Fig. 3 is a side elevation showing in dotted lines the initial engaging position with the 40 keeper, and in full lines, the final or operative engaging position;

Fig. 4 is a side elevation of a modified form of the invention;

Referring to the drawings, the hood catch, 45 according to the present embodiment of the invention, consists of a cylindrical barrel 10, flanged at its lower end, as at 11, to provide a reduced passage in which a rod 12 is slidably engaged, the end of the rod within the 50 barrel being provided with a fixed washer 13,

between which and the flange 11 a spring 14 is coiled about the rod.

The lower end of the rod 12 has a head or upset 15, engaged in a dome-shaped slotted base member 16 secured to the sill-piece of 55 the automobile frame.

The upper end of the barrel is threaded as at 17, and is screwed into the threaded socket 17 of a cap member 19, which closes the upper end of the barrel and forms a stop 60 to limit the upward movement of the rod 12 under the pressure of the spring. A clamping hook 20, and a handle 21, are formed integrally with the cap member.

The keeper comprises an elongated base 65 plate 22 riveted to the hood, provided at its vertical side edges and near its upper end with forwardly bent ears 23—23 supporting a transverse pin 24, upon which there is pivotally mounted a lever member comprising 70 side arms 25—25 and a transverse connecting portion 26. The side arms are rounded at their lower rearward edges to permit downward swinging movement and are angular at their upper rearward edges to provide 75 movement limiting abutment portions, a spring 27 coiled about the pin 24 and bearing at its respective ends upon the base plate and the connecting portion 26 adapted to normally retain the lever member in its raised 80 position, as indicated in Fig. 1. In its raised position the keeper lever is inclined downwardly, so that upon downward swinging there is a relatively rapid approach of the outer ends of the lever toward the hood sur- 85 face, the distance between said outer ends and the hood surface decreasing proportionately to the degree of rotation. A transverse pin 28 is provided between the outer ends of the arms 25, adapted for engagement by the 90 hook 20 of the hood catch.

An inclined cam portion 29 is formed up from the base of the keeper, and upon the hood catch barrel there is provided a projecting cam lug 30, having an inclined engaging face 31 adapted in the engaged relation of the catch to engage and bear upon the cam portion 29.

The operation is as follows:

As shown in Fig. 1 the catch is contracted, 100

the keeper-lever being raised, and the transverse pin 28 being at its maximum distance from the hood. The catch is pulled upwardly against the pressure of the spring to a point permitting engagement with the keeper, and is thereupon released, the keeper-lever rotating to a position as shown in full lines Fig. 3, the barrel moving downwardly and inwardly, pressing the cam lug 30 into engagement with the cam portion 29, so that the one-directional force of the spring is distributed into components exerting both a downward and an inward force or pressure upon the hood to securely clamp it in closed position. The pivoted keeper-lever, in addition to drawing the barrel inwardly, automatically compensates for any wear and irregularities.

In Fig. 4, I have illustrated a modified form of the invention in which an upwardly extending inclined cam lug 32 is provided on the base of the keeper, and which is engaged by a cam portion 33 on the barrel having a relatively long inclined under surface. The function and operation is the same as in the first embodiment.

I have illustrated and described preferred and satisfactory embodiments of the invention, but it will be obvious that changes may be made therein, within the spirit and scope thereof, as defined in the appended claims.

Having thus described my invention, what I claim and desire to secure by Letters Patent is:—

35 1. In a hood catch or the like, a hold down clamp, a keeper lever adapted to be mounted on the hood and to be engaged by said clamp, spring means acting to draw said clamp downwardly and swing said keeper lever inwardly toward the hood, and cam means between said clamp and the hood adapted to press the hood downwardly and inwardly under the action of said spring means.

45 2. In a hood catch or the like, a hold down clamp, a keeper lever adapted to be mounted on the hood and to be engaged by said clamp, spring means acting to draw said clamp downwardly and swing said keeper lever inwardly toward the hood, and cam means between said clamp and the hood adapted to press the hood downwardly and inwardly under the action of said spring means, said downward swinging of said keeper lever adapted to move said clamp laterally in the direction of said cam means under the action of said spring means.

50 3. In a hood catch or the like, a hold down clamp, a keeper lever adapted to be mounted on the hood to swing about a horizontal axis and including a clamp engaging portion outwardly spaced from said axis adapted to be engaged by said clamp, means adapted to normally retain said keeper lever in raised position with said clamp engaging portion outwardly spaced from the hood and per-

mitting yielding downward swinging movement whereby said clamp engaging portion moves toward the hood, spring means acting to draw said clamp downwardly and swing said keeper lever inwardly toward the hood, and cam means between said clamp and the hood adapted to press the hood downwardly and inwardly under the action of said spring means.

4. In a hood catch or the like, a hold down clamp, a keeper lever adapted to be mounted on the hood and to be engaged by said clamp, spring means acting to draw said clamp downwardly and swing said keeper lever inwardly toward the hood, and cam means between said clamp and the hood comprising an inclined cam surface on one of them and a cam projection on the other, adapted to press the hood downwardly and inwardly under the action of said spring means.

Signed at Bridgeport, county of Fairfield, and State of Connecticut, this 20th day of April, 1928.

RAYMOND G. MOORE.
